ELECTRIC LAMP CASING

Rene Marcel Angibaud, Vernon, Eure, France, assignor to Societe les Piles Wonder, Saint-Ouen, France

Filed Nov. 1, 1971, Ser. No. 194,801

Claims priority, application France May 25, 1971

Term of patent 14 years

Int. Cl. D26—02

U.S. Cl. D48—24

FIG. 1 is a front elevational view of an electric lamp casing embodying my new design;

FIG. 2 is a rear elevational view thereof;

FIG. 3 is an elevational view of one side thereof;

FIG. 4 is an elevational view of the other side thereof;

FIG. 5 is a top view thereof;

FIG. 6 is a bottom view thereof;

FIG. 7 is a side elevational view of a second embodiment of my design;

FIG. 8 is a top plan view thereof.

I claim:

The ornamental design for an electric lamp casing, as shown and described.
